UNITED STATES PATENT OFFICE

105,107

DESIGN FOR A GLASS BUILDING BLOCK

Harry S. Hower, Pittsburgh, Pa., assignor to
Corning Glass Works, Corning, N. Y., a cor-
poration of New York

Application March 16, 1937, Serial No. 68,204

Term of patent 14 years

To all whom it may concern:

Be it known that I, Harry S. Hower, a citizen
of the United States, residing at Pittsburgh, in the
county of Allegheny and State of Pennsylvania,
have invented a new, original, and ornamental
Design for a Glass Building Block, of which the
following is a specification, reference being had
to the accompanying drawing, forming part
thereof.

In the drawing Fig. 1 is a face view of a glass

building block showing my new design, and Fig. 2
a side view with a fragmentary corner portion
broken away to illustrate the interior configura-
tion that results in the appearance of my new
design.

I claim:

The ornamental design for a glass building
block, substantially as shown and described.

HARRY S. HOWER.
